THE NORRIS PETERS CO., PHOTO-LITHO., WASHINGTON, D. C.

UNITED STATES PATENT OFFICE.

WILLIAM GATES, OF WOODBRIDGE, AND LOUIS WILLIAM GATES, OF ORANGE, CONNECTICUT, ASSIGNORS OF TWO-FIFTHS TO JOHN H. BARNES, OF NORWICH, CONNECTICUT.

VALVE.

SPECIFICATION forming part of Letters Patent No. 702,417, dated June 17, 1902.

Application filed April 6, 1901. Serial No. 54,605. (No model.)

To all whom it may concern:

Be it known that we, WILLIAM GATES, residing at Woodbridge, and LOUIS WILLIAM GATES, residing at Orange, in the county of 5 New Haven and State of Connecticut, citizens of the United States, have invented certain new and useful Improvements in Valves, of which the following is a specification.

This invention relates to appliances adapted for use in drawing off liquids from containing vessels, and more particularly to straightway-valves designed for use in drawing off lager, ale, and the like from casks, kegs, or barrels.

15 In dispensing beer, ale, &c., to the consumer it is a common practice to effect the discharge of the liquid through a valve-controlled passage communicating with the keg, cask, or other vessel in which it is stored 20 through the tension exerted by carbonic-acid gas, air, &c., admitted under pressure to the vessel and serving to elevate the liquid through a pipe extending some distance below the surface of the liquid.

25 The present invention has for an object to provide an appliance simple in form and of cheap construction whereby access may be had to the interior of the keg, &c., for the insertion of the pipe or conduit through which 30 the liquid is to be discharged; and the invention provides, furthermore, an appliance that may be permanently secured to the keg and has no projecting parts liable to breakage or injury during transportation.

35 Referring to the drawings which accompany the present specification and which illustrate an embodiment of our invention, Figure 1 is partly an elevational and partly a sectional view representing in place an appliance of the foregoing character constructed according to our invention. Fig. 2 is a longitudinal section thereof on a somewhat enlarged scale and shows in connection with the valve proper and various parts a key for 40 operating the former. Fig. 3 is a top view of the appliance, the key shown in Fig. 2 being removed and the passage through the former being open. Fig. 4 is an elevational view of a certain valve-actuator embodied in the improvement. Fig. 5 is an end view thereof. Fig. 6 is a perspective view of the actuator

shown in Fig. 4 and the valve-casing of the appliance with certain of its parts. Fig. 7 is an elevational view of the valve-casing with the guard-piece shown in Fig. 5 in the position it occupies when the opening through the appliance is closed. Fig. 8 is a perspective view of a sliding plate embodied in the appliance and constituting the valve proper. Fig. 9 is a similar view of the valve-casing. 60 Fig. 10 is a similar view of the guard-piece. Fig. 11 is an elevational view of a key adapted for opening and closing the passage-way through the appliance.

Similar characters of reference designate 65 corresponding parts in all figures.

An appliance constructed according to the present invention is particularly adapted for permanent attachment to a cask, keg, or other vessel used for holding beer, ale, and other 70 beverages, and its construction embodies no projecting parts liable to injury or damage during handling or transportation, providing, furthermore, a straightway opening into the keg, &c., through which the discharge-pipe 75 for emptying the former may be inserted. Means also exist for the attachment of a conduit or pipe delivering carbonic-acid gas, air, or other fluid utilized for exerting a pressure upon the liquid within for the purpose of elevating the same through the inserted pipe.

The appliance is shown in Fig. 1 of the present drawings secured to the head of a keg A of liquor, and it comprises a tubular body portion (designated in a general way by B) adapted to be secured in a suitable opening in the vessel in any desired manner, the connection here shown comprising a screw-thread b on the outer surface of the body portion, by which means the latter is adapted to be 90 screwed into the vessel until it abuts against a shoulder b', formed by a flange on the body portion and preferably entering a countersunk recess to bring the outer face of the body portion substantially flush with the 95 outer surface of the head, as indicated in Figs. 1 and 2.

The valve proper of the appliance serves to control the continuity of the passage through the bore of the body-piece and in the preferred construction is mounted in a valve-casing, which may be attached in any desired

way to the body portion of the appliance, the provision of an independent valve-casing facilitating the manufacture and assembling of the parts. The valve proper (designated in 5 a general way by C) is conveniently made in the form of a sliding plate, which is adapted to move transversely to the passage through the body portion, being mounted in a suitable guideway 2, formed in the valve-casing, (designated in a general way herein by D.) The guideway in the valve-casing as formed in the present instance is a T-slot at the lower portion of the casing, the sliding plate constituting the valve having a rib 3, forming 15 one its guiding-surfaces. The sliding plate may be held against its seat to form a sliding joint by some spring-like device, this device as constructed in the present case comprising springs 4 and 4, inserted between the sliding plate and overlapping portions of the guideway formed in the valve-casing.

For operating the valve we provide a valve-actuator conveniently consisting of an oscillatory member which serves to transmit motion from the operating-key (to be described) 25 to the valve-plate and effect the movement of the latter in its guide. In the form herein shown this actuator (designated in a general way by E) comprises an annular part 5, whose central opening forms part of the passage through the appliance. The actuator is mounted to rotate upon its axis in the valve-casing, being confined to its proper movement according to the illustrated construction by bearing portions 6, (any suitable number,) formed in the valve-casing, a circular flange 6' within the body portion, and the inner surface of the valve-casing. Projecting from the annular part of the actuator is a pin 35 7, which enters a recess 7' in the sliding or valve plate and serves to effect the movement of this valve-plate when the actuator is turned upon its axis, an elongated opening 8 being provided in the valve-casing to permit 40 of the movement of the projecting pin and having shoulders at its ends determining the extent of movement of the latter. A friction device for preventing too free a movement of the actuator is shown, consisting of a 45 spring 9, whose curved end is adapted to bear against the periphery of the actuator.

A key for shifting the valve-plate is adapted to pass down through the bore of the body portion and engage with the valve-actuator. 50 The construction for effecting this engagement comprises in the present embodiment projections 11 11, (two such being shown,) extending from the actuator axially of the bore of the body portion and adapted to engage 55 with corresponding notches 11' 11', formed at the end of the key F. The key is hollow or tubular, and from the foregoing description it is evident that when inserted in place and turned upon its axis the resulting movement 60 of the actuator will effect the shifting of the valve-plate.

The key serves as a convenient means for

the inlet of the pressure medium, and for this purpose it is provided with a tubular offset 12, to which a conduit 13, delivering the pressure medium, may be attached. 70

Through the tubular key when turned to a position in which the valve-plate is opened and through the body and valve portions of the appliance may be passed the pipe or conduit (designated in a general way by G) serving for the discharge of the containing liquid and which terminates adjacent to the bottom of the vessel. This discharge-pipe G is somewhat smaller in diameter than the diameter 80 of the straightway passage to admit the pressure medium to the interior of the vessel, and for the purpose of making a tight joint with the body-piece to prevent a leakage outward around the key there is provided suitable 85 packing 14 and a co-operating seat 14' therefor. This packing may be pressed securely against the seat by providing inclined or cam-shaped ears 15 15' on the key, which as the latter is inserted in place pass through corresponding recesses 15" and 15'', respectively, in the body portion and serve by their coaction with co-operative portions 15⁴ 15⁵, respectively formed by circular slots in the body portion, to press the packing firmly against its seat. 90 This construction also locks the key in place until it has been turned back to its entering position—that is, to a position corresponding to a closed position of the valve-plate—and if the ears and corresponding recesses are made 100 of different widths pair and pair, as shown, will permit the insertion of the key in a definite position only of the latter.

The tubular key is furnished at its upper or outer portion with a suitable means for 105 connecting it by a pressure-tight joint with the discharge-tube G. For instance, it may be connected to the latter by a coupling 16, and the outer delivery-tube g for delivering the liquid to the desired point may be connected 110 directly with it, or the discharge-tube may be provided with an attached valve 17 and a coupling (designated by 18) utilized for securing the delivery-tube g to this valve 17.

To prevent the forcible insertion of a discharge-pipe through the appliance with probable resultant injury to the valve-plate when the latter is in a closed position, there is provided in the present embodiment a guard-piece, (designated in a general way by H,) 115 which consists of a finger provided with a pivot-pin 20, entering a pivotal recess in the valve-casing and adapted to pass through an opening 21 in the annular portion of the valve-actuator. It will be noticed, particularly in 120 Fig. 7, that the shoulders at the ends of this recess are somewhat curved, constituting thus a means for securing the operation of the guard-piece. When the valve-actuator is turned to a position in which the valve-plate 125 is closed, the shoulder 22, impinging against the side of the guard-piece, urges the same into a position in which it extends across the 130 passage through the appliance. When, how-

ever, the actuator is rotated to shift the valve-plate and open the passage, the opposite shoulder operating in like manner serves to withdraw the guard-piece from its protruding

5 position across the passage; but the parts are so constructed and related that the shoulder 22 does not assume a position in which the guard-piece is permitted to be withdrawn from its protruding position until the valve-
10 plate has been moved to substantially the end of its opening movement. Thus it will be seen that the guard-piece, which, it may be stated, is located in a different plane to that which the valve-plate occupies, serves
15 to protect the latter in all positions in which it extends into and across the passage.

The valve-plate is shown provided with a concave notch 23 at one end, which notch is brought into alinement with the through-
20 passage when this plate is shifted to open the passage.

Having described our invention, we claim—

1. In an appliance of the character described, the combination with a valve move-
25 able to and fro in a straight line, of a tubular operating-key provided with means for the attachment of a conduit for the delivery of a pressure medium.

2. In an appliance of the character de-
30 scribed, the combination with a valve move-
able to and fro in a straight line and a tubular operating-key provided with means for the attachment of a conduit for the delivery
35 of a pressure medium, of a discharge-pipe adapted to pass through said tubular key.

3. In an appliance of the character de-
scribed, the combination with a valve movable to and fro in a straight line, a body portion, a valve-casing, and a tubular operating-key
40 provided with means for the attachment of a conduit for the delivery of a pressure medium, of a discharge-pipe adapted to pass through said tubular key.

4. An appliance of the character de-
45 scribed having a body portion adapted to be attached to the containing vessel with its exterior surface substantially flush with the exterior surface of the vessel, in combination with a valve-casing secured to the body por-
50 tion, and a valve mounted in the casing and movable in a straight line transversely to the axis of the opening through the appliance.

5. In an appliance of the character de-
55 scribed, the combination with a body portion adapted to be secured to a vessel, of a valve-
casing secured to the body portion; a valve mounted in the casing to slide to and fro in a straight line; a valve-actuator mounted in the appliance; and a key for operating the valve-
60 actuator.

6. In an appliance of the character de-
65 scribed, the combination with a body portion adapted to be secured to a vessel, of a valve-
casing secured to the body portion; a valve mounted in the casing to slide to and fro in a straight line; a valve-actuator mounted in the appliance; and a tubular key separate

from and adapted to be engaged with and disengaged from the actuator for operating the valve-actuator.

7. In an appliance of the character de-
scribed, the combination with a tubular body portion whose bore is adapted to receive an operating-key, of a sliding plate constituting a valve; means for guiding such plate and confining the same to a to-and-fro rectilinear movement; and a valve-actuator separate from the sliding plate and the operating-key, and having projecting pins engaging with the sliding plate and adapted to engage with the operating-key.

8. The combination in an appliance of the character described, of a body portion; a valve-
85 casing secured to the body portion; a sliding plate constituting a valve movable to and fro in a straight line; an actuator mounted in the valve-casing and provided with a pin engag-
90 ing with the sliding plate; and shoulders formed in said valve-casing for limiting the movement of the actuator.

9. The combination with a body portion, of a valve-casing secured thereto; a sliding plate constituting a valve mounted in the valve-casing to slide to and fro in a straight line; and a valve-actuator provided with a project-
95 ing pin engaging with the sliding plate and with projections adapted to engage with an operating-key insertible in the bore of said body portion.

10. In an appliance of the character de-
scribed, the combination with a tubular body portion whose bore is adapted to receive an operating-key, of a valve; means for guiding the valve and confining the same to a to-
105 and-fro rectilinear movement; a rotatable valve-actuator separate from the valve and having projecting pins engaging with the valve and adapted to engage with the operating-key; and a friction device for preventing the valve from moving too freely.

11. In an appliance of the character de-
scribed, the combination, of a body portion; a valve-casing; a sliding plate constituting a valve movable to and fro in a straight line; a rotatable valve-actuator for actuating the
115 sliding plate; a key insertible in the bore of said body portion and adapted to engage with the valve-actuator; and a friction device for preventing the free movement of the actuator.

12. The combination with a sliding plate constituting a valve; an actuator for actuating the sliding plate; an independent guard-
125 piece extending across the passage through the valve when the sliding plate is closed; and means for operating the actuator to open the passage through the valve and shift the guard-piece away from said passage.

13. The combination with a sliding plate constituting a valve; an actuator for actuating the sliding plate; an independent guard-
130 piece consisting of a pivoted finger extending across the passage through the valve when the sliding plate is closed; and means for

operating the actuator to open the passage through the valve and shift the guard-piece away from said passage.

14. In an appliance of the character described, the combination with a body portion; a valve-casing secured to said body portion; a sliding plate constituting a valve mounted in said valve-casing; a valve-actuator for actuating the sliding plate provided with opposite shoulders; and an independent guard-piece shiftable into and out of position across the opening through the valve by the operation of the shoulders on the valve-actuator.

15. In an appliance of the character described, the combination of a body portion; a valve-plate movable to and fro in a straight line transversely to the axis of the bore extending through the body portion; a key for effecting the movement of the valve-plate; and means for effecting the longitudinal movement of the key when operated to open the valve to form a tight joint with the body portion.

16. In an appliance of the character described, the combination with a valve-casing, of a valve mounted therein; means for guiding the valve and confining the same to a to-and-fro rectilinear movement; and a rotatable actuator separate from the valve and the

operating-key of the device, and having projecting pins engaging with the valve and adapted to engage with the operating-key, whereby motion may be transmitted from the key to the valve.

17. In an appliance of the character described, the combination of a sliding plate constituting a valve; a valve-casing; an actuator extending through the casing and engaging with said sliding plate; means for preventing the free movement of the sliding plate; a tubular body portion; a tubular key insertible in the bore of said body portion and adapted to engage with the valve-actuator; an independent guard-piece actuated by the operation of said key; means for attaching a conduit to said tubular key for the delivery of a pressure medium; a discharge-pipe adapted to pass through said tubular key; and means for effecting the longitudinal movement of the key to form a tight joint when the key is operated to open the valve.
